DERRICK STRUCTURE

Harry H. Franks, Tulsa, Okla., assignor to Franks
Manufacturing Corporation, Tulsa, Okla., a
corporation of Oklahoma

Application August 12, 1938, Serial No. 224,513

1 Claim. (Cl. 189—15)

This invention relates to derrick structures and particularly to portable type derricks which are adapted to be quickly and easily folded or collapsed into a compact form suitable for convenient transportation from place to place.

The development of such portable drilling rigs has proceeded at such a rapid pace that they have now been designed and actually employed successfully to drill wells ranging in depth to 10 5,000 feet or more. Such deep drilling requires, among other necessary equipment, relatively tall and heavy derricks in order to handle the long and heavy strings of drill pipe and casing necessitated by such deep wells. Derricks, as much as 15 ninety feet in height and of great strength are required, and such derricks, exclusive of auxiliary equipment, will weigh many thousands of pounds. Since almost all states have formulated laws and regulations greatly limiting the horizontal and 20 vertical dimensions of structures which may be transported over their highways, obviously, it has become an important problem to construct a form of derrick large enough for deep drilling but which may be mounted on a transporting vehicle 25 and yet kept within the dimensional limits prescribed by such laws and regulations.

The base dimensions of derricks of the height above indicated are generally such that when the derrick is in horizontal transport position, the height above the ground level will exceed the 30 various state regulations and so must be restricted, and this invention contemplates a derrick structure having a lower or base section, the front and rear panels of which may be folded together into a comparatively flat structure when 35 moved to transport position, and expanded to full base dimensions when raised to operating position, and which will be limited in length, but adapted to receive additional upper sections, 40 when in operating position, in order to increase its length to any length desired to meet particular drilling conditions.

Therefore, a principal object of this invention is 45 to provide a new form of derrick structure which may be pivotally mounted on a transport base and which may be folded for transporting into a structure of reduced dimensions.

Another object is to provide a portable derrick 50 structure which folds upon itself when lowered to

a transport position and which unfolds when raised to an operating position.

A more specific object is to provide a derrick structure wherein the front and rear legs of the derrick on the same side thereof are connected together by girders hingedly attached at each end to the legs, whereby the front and rear panels of the derrick may be folded together when the derrick is lowered to transport position and expanded to full dimensions when raised to operating position.

Another object is to provide a portable, folding derrick base member upon which additional derrick sections may be assembled to provide a structure of any desired height.

Still another object is to provide a folding derrick structure having one pair of its corner legs constructed in the form of cantilever trusses pivotally mounted on a supporting base.

Other and more specific objects and advantages will become apparent from the following description and the accompanying drawings which illustrate one form of derrick structure in accordance with this invention.

In the drawings:

Fig. 1 is a side view showing the derrick structure of this invention mounted on a transporting vehicle. The derrick base member is shown in vertical operating position in full lines, the top portion thereof being in dotted lines, and partially lowered toward transport position in dotted outlines.

Fig. 2 is an enlarged side view of the lower portion of the structure shown in Fig. 1.

Fig. 3 is an end view of the portion of the structure shown in Fig. 2.

Figs. 4 and 5 are details of one of the hinge connections between one of the derrick legs and one of the connecting girders.

Fig. 6 is a horizontal section taken along line 40 6—6 of Fig. 4.

Referring to the drawings, and to Fig. 1 in particular, a derrick structure in accordance with this invention, and designated generally by the numeral 1, is shown mounted on a frame 2 which 45 is in turn mounted on a mobile base such as trailer 3. The transport vehicle may also be an automobile truck or skids as desired. The derrick 1 is pivotally mounted on a frame 2 by means of hinge bar 4 extending horizontally between oppo- 50

site side members of the derrick and rotatively supported on upright members 5 carried by frame 2 and extending upwardly therefrom. The derrick structure is raised and lowered between operating and transport positions about hinge bar 4 by means of a pitman 6 which has one end rotatively attached to the lower end of derrick 1 and the other journaled in a cross head member 7 which is longitudinally movable in an outer 10 guideway of frame 2.

The derrick structure 1 includes front legs 8-8, preferably though not necessarily of tubular construction, which are spaced apart a distance suitable for the particular derrick desired, but ordinarily 15 are less than eight feet apart, since this distance is the width limit generally prescribed by highway laws and regulations. The legs 8-8, preferably slope inwardly toward the vertical axis of the derrick. The rear legs of the derrick, 20 designated generally by the numerals 9-9, comprise structures in the form of cantilever trusses, the front stringers 10-10 being parallel to front legs 8-8 and the rear stringers 11-11 sloping toward the vertical axis of the derrick oppositely 25 to front legs 8-8 and at substantially the same angle, with the result that stringers 10 and 11 of each truss meet at an acute angle at a point toward the upper portion of the derrick. The point 30 at which the stringers meet depends, of course, upon the angle between them, and this is determined by the length and size of each particular derrick. The stringers 10 and 11 of each truss are also of tubular construction and are strongly 35 cross braced by bracing members 12 thus completing the truss structures.

Each front leg 8 is hingedly connected to the adjacent stringer 10 on the same side of the derrick by a plurality of vertically spaced, horizontal girders 13. The opposite ends of each 40 girders 13 is connected by hinge connections, denoted generally by the numerals 14-14, to the front leg 8 and its corresponding stringer 10. Front legs 8-8 are spaced apart and rigidly connected together by means of girders 15 and braces 45 16, forming the front panel of the derrick structure (Fig. 3), while stringers 11-11 are likewise spaced apart and rigidly connected to each other by similar girders and braces to form the rear 50 panel of the derrick structure. Since legs 8-8 and stringers 10-10 are parallel, all of the girders 13 will be equal in length, and the purpose of this arrangement will be explained in greater detail hereinafter.

The portion of the derrick structure which 55 includes the trusses 9-9 and front legs 8-8 forms a derrick base member, upon the upper part of which a superstructure S, consisting of additional derrick sections, crown block, platform, etc., may be manually superimposed to increase the overall height of the derrick to any desired dimensions and to complete the structure in all its parts. Such superstructure, which is more or less conventional in construction, is shown in dotted 60 lines in Fig. 1. This superstructure is generally added to the base member in portions in the more or less conventional manner in which derricks are 65 normally constructed.

The form of construction of hinge connections 70 14 is shown in detail in Figs. 4 to 6, inclusive, and consists of a hollow sleeve 17 which extends transversely through the end of girder 13, which is preferably of tubular construction because of the greater strength of such construction. Sleeve 75 17 is slightly longer than the diameter of girder

13 and its ends project from each side of girder 13, to which sleeve 17 is rigidly welded. A second hollow sleeve 18 is mounted within the bore of sleeve 17 and is closely fitting therein, being inserted therein ordinarily by pressing or driving. Sleeve 18 is longer than sleeve 17 and positioned therein so that its ends project from each end of sleeve 17 to form hollow trunnions 19 which are journaled in registering circular openings 20-20 provided in a pair of connector plates 10 21-21, which are welded or otherwise rigidly attached to opposite sides of one of the legs 8-8 or stringers 10-10, depending upon which end of girder 13 is being considered.

In assembling girder 13 to legs 8 and stringer 15 10 by means of the hinge connection 14, an end of the girder carrying sleeve 17 only, is inserted between plates 21-21 with the bore of sleeve 17 in registration with openings 20-20, and then sleeve 18 is inserted through one of the openings 20 20 and the bore of sleeve 17 until the other end of sleeve 18 is received in the opposite opening 20, thus completing the hinge connection of the girder to either the leg 8 or stringer 10 as the case 25 may be. The projecting ends of sleeve 17, which are larger than the diameter of openings 20, act as spacers between plates 21-21.

When the derrick structure is in vertical operating position, the structure is firmly braced between the legs 8 and the corresponding stringers 10 by means of cross braces 22, shown in dotted outlines in Fig. 1 and fragmentarily, in full lines, in Figs. 4 to 6, which extend between diagonally opposite hinge connections 14 and are connected 30 thereto by means of bolts 23 which are inserted through the bores of sleeves 18 and through appropriate openings in the ends of cross braces 22. Two cross braces 22 are connected to each hinge connection 14 at opposite sides thereof, one of the cross braces extending downwardly and the other upwardly, as illustrated in detail in Figs. 4 to 6.

Legs 8-8 and stringers 11-11, which form the corner posts of the derrick, are provided with adjustable feet 24-24 for leveling the corners of 45 the derrick when in operating position.

The operation of the above described derrick structure is as follows:

Starting with the derrick in vertical operating 50 position, with cross braces 22 and superstructure S in place, it is desired to lower the derrick to transport position. Superstructure S and cross braces 22 are first removed from the more permanent portions of the structure and by moving cross head 7 toward the rear end of frame 2, (considering the derrick to be mounted on the rear end of frame 2) pitman 6 applies a thrust against the lower extremity of the derrick, which causes the derrick to rotate about pivot bar 4, the upper portion of the derrick coming to rest finally on the forward portion of the transport vehicle, as shown in dotted outlines in Figs. 1 and 2 particularly. As the derrick swings rearwardly from its vertical position, the hinged connections of 55 girders 13 between legs 8 and stringers 10 permits the front panel of the derrick to slide downwardly relative to the rear panel of the derrick and parallel thereto and assume a final position immediately adjacent to, and superimposed on stringers 70 10, as shown in dotted outlines in Fig. 2. By making stringers 10 and legs 8 parallel to each other, and thereby making girders 13 of equal length, legs 8 and stringers 10 maintain their parallelism throughout the lowering operation 75

and thus permit the front panel to fold down completely on stringers 10. As a result the maximum dimension of the structure, when in transport position, will be only the width, from front 5 to back, of the widest portion of trusses 9. Consequently, the height of the structure above the ground level when in transport position will be greatly reduced and preferably to a dimension which will be within the prescribed dimensional 10 limits of highway laws.

When the structure is raised to vertical operating position, the reverse of the above movements of the parts of the structure takes place and the derrick expands to its full base dimensions, whereupon the superstructure S and cross braces 22 are put in place to complete the structure. It will be evident from the drawings that when the derrick is folded, legs 8-8 project rearwardly beyond the ends of stringers 10 and 11 a 15 distance equal to the length of girders 13. When the derrick is being raised, the ends of legs 8 in their downward arc strike the ground before the ends of stringers 10 and 11 and this arrangement provides an upward pry upon legs 8-8 by the 20 ground surface and starts the expansive movement of the structure. Legs 8 are also longer than trusses 9 and extend above the upper ends of the trusses in vertical position, and provide 25 means for more effectively tying superstructure S to the derrick base structure.

In the foregoing, the general form of derrick structure described is that of a pyramid, having a rectangular base section, and in which the rear legs 9-9 are in the form of trusses, whose stringers are equal in length and with their base members form isosceles triangles. This form of construction is preferred because of its greater strength and rigidity, and by positioning the transverse pivot bar 4 between the stringers near 30 the base of the structure, a cantilever arrangement is provided which has great strength and readily lends itself to controlled raising and lowering between transport and operating positions, a very important consideration in the handling 35 of the heavy type derricks referred to above.

It will be understood, however, that the truss construction of the rear legs may be dispensed with and stringers 10 alone with legs 8 used to form the corner legs of the derrick. However, 40 in this case, in order to maintain their parallelism so that the derrick may be folded as described, the derrick when in operating position necessarily will be vertical in order to maintain even loading conditions thereon. This form of construction 45 may be useful for handling comparatively light loads, but as indicated, the pyramid construction,

including the truss construction of legs 9-9, is preferable under most conditions.

Derrick structures in accordance with this invention have been constructed having the following specifications:

Over-all height to top of superstruc-				
ture S	84 feet			
Height to top of legs 9-9	55 feet			
Width at base	7 ft.-7 in.	10		
Depth at base (incl. trusses) expanded	15 feet			
Depth at base—folded	6 ft.-7 in.			
Weight (exclusive of S and braces 22)	10,200 lbs.			
Pipe capacity of derrick—6 1/4 inch pipe	6,000 feet	15		

Numerous modifications and alterations may be made in the size, form and arrangement of details of the derrick structure of this invention without departing from the scope of the appended 20 claim.

What I claim and desire to secure by Letters Patent is:

In a portable derrick structure, a mobile base, a derrick mounted on said base adjacent one end thereof, comprising a rear panel positioned transversely of said base and having longitudinal edge members in the form of trusses positioned at right angles to the plane of the rear panel, each of said truss members comprising front and 25 rear stringers spaced apart at their lower ends and converging at their upper ends, a pivot bar extending horizontally between said trusses in the vicinity of the lower ends thereof and journaled to support members extending upwardly 30 from said base, a front panel parallel to and spaced from the plane of the front stringers of the truss members, means for folding the front panel downwardly against the rear panel comprising a plurality of pivotally mounted girders 35 extending between the longitudinal edges of said front panel and the adjacent truss stringers, whereby when said derrick is moved to transport position on said base, said front panel will assume a position adjacent to the front stringers 40 of said truss members, with the bottom portion of the front panel projecting beyond the ends of the front truss stringers a distance substantially equal to the length of one of the pivoted girders, and when raised to vertical operating 45 position will be spaced from said truss members a distance equal to the length of a girder and means for moving said derrick between transport and vertical operating positions.

HARRY H. FRANKS.
